RETRACTABLE-NIB FOUNTAIN PEN

Shoichiro Itoh, Hatanoshi, Japan, assignor to The Pilot
Pen Co., Ltd., Tokyo, Japan

Filed Nov. 4, 1974, Ser. No. 520,715

Term of patent 14 years

Int. Cl. D19—06

U.S. Cl. D19—41

FIG. 5.

FIG. 6.

FIG. 7.

FIG. 8.

FIG. 1 is a front elevational view of a retractable-nib fountain pen showing my design with the nib in an extended condition;

FIG. 2 is a front elevational view thereof with the nib retracted;

FIG. 3 is a rear elevational view with the nib extended;

FIG. 4 is a rear elevational view with the nib retracted;

FIG. 5 is a right side elevational view with the nib extended;

FIG. 6 is a right side elevational view with the nib retracted;

FIG. 7 is an inverted left side elevational view with the nib extended;

FIG. 8 is an inverted left side elevational view with the nib retracted;

FIG. 9 is an enlarged scale top plan view of FIG. 8;

FIG. 10 is a bottom plan view thereof; and

FIG. 11 is a perspective view with the nib in an extended position.

I claim:

The ornamental design for a retractable-nib fountain pen, as shown and described.
